EXPLOSIVE COMPRISING POLYNITRO HETERO-CYCLIC AND NITROAROMATIC COMPOUNDS

Elbert E. De Maris, Mantua, N.J., assignor to E. I. du Pont de Nemours and Company, Wilmington, Del., a corporation of Delaware

No Drawing. Filed Mar. 28, 1963, Ser. No. 268,554

5 Claims. (Cl. 149—106)

The present invention relates to high explosive compositions capable of being compressed readily into dense shaped articles having high thermal stability and compressive strength.

In oil-well perforating operations, it is desirable to use an explosive in the form of dense shaped articles having sufficient compressive strength to obviate the need for a supporting container, and high thermal stability, so that the explosive is not adversely affected by the temperatures encountered in the wells, i.e., temperatures exceeding 350° F. High density is desirable since the higher the density, the closer the explosive properties approach theoretical.

It recently has been discovered that tetranitro derivatives of certain dibenzotetraazapentalenes, i.e., tetranitro-2,3; 5,6-dibenzo-1,3a,4,6a-tetraazapentalene and tetranitro-2,3; 4,5-dibenzo-1,3a,6,6a-tetraazapentalene, are explosive compounds of unusually high thermal stability. The working of these compounds into shaped articles presents considerable difficulty, however. In order to produce dense articles therefrom, i.e., articles having a density of at least about 1.70 grams per cubic centimeter, it is necessary to apply extremely high compressive pressures, e.g., about 40,000 pounds per square inch, to the material over extended periods of time, e.g., for about 0.5–2 hours.

The present invention provides new explosive compositions which can be compressed readily into dense shaped articles of strength, stability, and explosive properties equivalent to those of articles made from compositions consisting solely of the aforementioned tetranitro compounds.

The compositions of this invention comprise a mixture of at least one polynitro heterocyclic compound selected from the group consisting of tetranitro-2,3;5,6-dibenzo-1,3a,4,6a-tetraazapentalene and tetranitro-2,3;4,5-dibenzo-1,3a,6,6a-tetraazapentalene and from about 1 to 20%, based on the weight of the mixture, of at least one aromatic compound of 6 to 7 carbon atoms bearing 3 nitro groups as the sole inorganic substituents, that is, a trinitrobenzene, a trinitrotoluene, or a mixture thereof. Of the aromatic trinitro additives, trinitrobenzenes are preferred because of their thermal stability. Of the isomeric trinitrobenzenes, 1,3,5-trinitrobenzene is particularly preferred because of the optimum processing qualities it imparts to compositions of this invention, because of the optimum strength and stability of products formed therewith and because of its ready availability.

The explosive compositions of this invention can be formed into shaped articles having a density of at least about 1.70 grams per cubic centimeter by application of compressive pressures of only 10,000 pounds per square inch for a period of only 10 minutes. When higher pressures are used, the application time need be only 1 minute. In contrast to this, the aforementioned polynitro heterocyclic compounds per se require much severer conditions applied over longer periods to reach such densities. In addition, at pressures of 40,000 pounds per square inch they reach a maximum density after two hours' application time which is lower than the density attained in 1 minute with the novel compositions of this invention. In addition to having high density, shaped articles produced from the present com-

2

positions exhibit compressive strengths above 4,000 pounds per square inch and are suitable for use without a supporting container.

The compositions of this invention have outstanding thermal stability and the properties of a high explosive. The preferred compositions of this invention are stable at temperatures above 600° F., are initiated by conventional blasting caps, detonate at about 7000 meters per second, and have an explosive power comparable to that of the aforementioned polynitro heterocyclic compounds.

The compounds tetranitro-2,3;5,6-dibenzo-1,3a,4,6a-tetraazapentalene and tetranitro-2,3;4,5-dibenzo-1,3a,6,6a-tetraazapentalene are represented by the following structural formulas, respectively:

and

Obviously there are numerous possible isomers of these compounds based upon the relative positions of the nitro groups on each benzene ring. All of the possible isomers of each compound are believed to be present to a greater or lesser extent in each product. For purposes of the present invention, there is no material distinction between any such isomers, i.e., the stability and explosive properties of these isomers appear to be quite similar and the novel compositions of this invention may include any of these isomers individually or a combination of any such isomers in any proportion. Actually, separation of the isomers is very difficult because of the similarity in their properties and synthesis of either of the compounds would normally result in a mixture of isomers. This is satisfactory insofar as explosive applications are concerned and the product may be used directly in this form. Throughout this application, reference to the two tetranitro compounds is understood to include any and all such isomers and/or any mixture of such isomers in any proportion.

The tetranitro-2,3;5,6-dibenzo-1,3a,4,6a-tetraazapentalene can be prepared by mixing one part of 2,3;5,6-dibenzo-1,3a,4,6a-tetraazapentalene in concentrated sulfuric acid with 30 parts of red fuming nitric acid with slight cooling, allowing it to react for 15 minutes at about ambient temperature, heating the resulting product at 60° C. for an additional 15 minutes, then precipitating the tetranitro derivative by cooling the reaction mixture and pouring it into five times its volume of ice water. The 2,3;5,6-dibenzo-1,3a,4,6a-tetraazapentalene can be prepared as described in Reissue Patent No. 25,238. The tetranitro-2,3;4,5-dibenzo-1,3a,6,6a-tetraazapentalene can be prepared by similar procedures from 2,3;4,5-dibenzo-1,3a,6,6a-tetraazapentalene. As described more fully in copending application Serial No. 252,059, filed January 17, 1963, 2,3;4,5-dibenzo-1,3a,6,6a-tetraazapentalene can be prepared by reducing 1-(o-nitrophenyl)-1,2,3-benzotriazole to 1-(o-aminophenyl)-1,2,3-benzotriazole, reacting the resulting product successively with an alkali metal nitrite and an alkali metal azide in

the presence of a strong acid to yield the corresponding azido derivative and heating such azido derivative at a temperature of at least about 100° C.

The ingredients of the present explosive composition can be mixed together in any convenient manner. For example, the polynitro heterocyclic compound can be mixed with a solution of trinitrobenzene or trinitrotoluene in a polar solvent, e.g., a ketone, ester, or alcohol, and the solvent thereafter evaporated. Alternatively, the polynitro heterocyclic compound can be mixed with molten trinitrobenzene or trinitrotoluene, and the latter then allowed to solidify.

The compositions of this invention can contain the aforementioned polynitro heterocyclic compounds and aromatic nitro additive alone or in combination with other conventional additives, for example, inorganic oxidizing agents such as potassium perchlorate and lead dinitrate, preferably in amounts up to 10% by weight. Larger amounts of such additives also may be employed, however, for example a stoichiometric amount of oxidizing agent, e.g., about 65% potassium perchlorate. Also, up to 10% by weight of auxiliary binding agents such as those described in copending application Serial No. 118,260, filed June 20, 1961, now U.S. Patent No. 3,089,796, can be added thereto.

As stated previously, the amount of trinitrobenzene or trinitrotoluene in the present explosive compositions can vary from about 1% to about 20% by weight. Generally, optimum thermal stability and ease of compressing into dense shaped objects are found in compositions containing from about 2% to about 5% of the aromatic trinitro compound, and such compositions are preferred. In addition to these, desirable compositions are those containing as little as 1% of trinitrobenzene or trinitrotoluene and small quantities of other additives, such as those mentioned above, which may enhance the compressibility of the composition. Compositions containing less than 1% of the aromatic trinitro compound are not desirable because the forming of shaped articles therefrom begins to require severe conditions of pressure and time. The aromatic trinitro compound can be used in amounts up to about 20% by weight of the composition, if a lowered thermal stability can be tolerated. Compositions containing greater than 20% of trinitrobenzene or trinitrotoluene do not exhibit the outstanding thermal stability of the compositions of this invention. In compositions containing substantially more than about 5% of the aromatic trinitro compound, it may be helpful to incorporate small amounts of a gelling agent such as silicon dioxide to prevent leakage of the trinitro compound from the composition during pressure at elevated temperatures.

The preparation of shaped articles from the present explosive compositions can be effected in any desired manner. No binder material is required. As is shown in the following examples, the compositions can be formed into shaped articles of density greater than 1.70 grams per cubic centimeter when pressures of 10,000 pounds per square inch are applied for 10 minutes. Higher pressures require less compression time. Generally, it is helpful to heat the mixture at about 150° to about 225° C. during compression, and also to preheat at this temperature for a minute or so prior to compression.

By employing a suitably shaped mold, shaped articles of any desired configuration can be obtained. Thus, the compositions of this invention can be shaped into briquette-like pellets useful as such as a high explosive or as a mold charge to make other shaped articles. By using a cylindrical mold with a conical protrusion in one end thereof, shaped charges can be prepared. Such shaped charges can be either used per se or with a metallic liner in the conical indentation therein as described, for example, in U.S. Patents 2,399,211 and 2,563,131. The compositions of this invention can also be compressed into polyhedral or cylindrical blocks which can be used as high temperature explosive charges or as primers.

To more fully describe the preparation and properties of the new explosive compositions of this invention, reference is now made to the following examples which are intended to be illustrative only and not as limiting the invention in any manner.

In the examples, a Dillon Model L Universal Testing Machine with a compression cage, 0-10,000-pound dynamometer, and powered with an air motor was used to compress the pellets. The compressive strength was determined according to ASTM Test Method D695-54, as described in ASTM Standards, 1958 Edition, Part 9, pages 244-251.

Example 1

(A) A solution of 1 gram of 1,3,5-trinitrobenzene in 15 5 milliliters of acetone is poured over 19 grams of tetrani-
5 tro-2,3;5,6-dibenzo-1,3a,4,6a-tetraazapentalene which has been wetted with 10 milliliters of acetone. After stirring for 2-3 minutes to insure a uniform mixture, the acetone then is evaporated on a steam bath while the 20 mixture is stirred leaving 20 grams of an orange-red powder. To determine the thermal behavior of the composition, a 25-60 milligram sample is heated at a rate of 7.5° C. per minute. The trinitrobenzene portion melts at 123° C., there is evidence of some decomposition beginning at 325° C., and the major part of the sample 25 decomposes at 379° C.

Two and one-half gram portions of the powder are pelleted in a die at 200° C. The die is tapered, having a maximum diameter of 0.5 inch and a maximum depth 30 of 0.5 inch. The powder is heated in the die for 1 minute at 200° C., and then is pressed at the same temperature by application of 10,000 pounds per square inch pressure for a period of ten minutes. The pellets are then ejected from the die while hot. They have a density of 1.754 grams per cubic centimeter, and exhibit compressive strengths of about 4400 pounds per square inch. The pelleted composition can be initiated by a conventional blasting cap, and detonates at a velocity of 6,930 meters 35 per second.

To test explosive power, a pellet is placed on a 0.5-inch thick 1018 cold-rolled steel plate, which in turn rests on a larger plate made of the same material. The pellet is initiated by a conventional blasting cap, and the resulting dent made in the steel is measured to the nearest 40 thousandth inch. The dent value for this pellet is 0.059 inch, the same as the value obtained with a pellet of 100% tetrani-2,3;5,6-dibenzo-1,3a,4,6a-tetraazapentalene of density 1.67 grams per cubic centimeter.

(B) To contrast these results with the results obtained 50 when tetrani-2,3;5,6-dibenzo-1,3a,4,6a-tetraazapentalene alone is formed into pellets, the tetraniro compound is pelleted in the same way as the composition described in A. The density is only 1.28 grams per cubic centimeter, and the compressive strength 1000 pounds per square inch. The detonation velocity is 4500 meters 55 per second.

Example 2

The procedure of Example 1(A) is repeated while 60 varying one or more of the conditions, e.g., pressure, compression time, and composition pelleted. The results are shown in the following table.

Wt. ratio of trinitro benzene to tetraniro compd.	Time heated before pressing (min.)	Pressure (p.s.i.)	Compre- sion Time (min.)	Density (g./cc.)
2/98	1	10,000	10	1.70
5/95	1	40,000	10	1.75
0/100	1	40,000	10	1.66
5/95	10	40,000	1	1.73
0/100	10	40,000	1	1.64
0/100	-----	40,000	120	1.72
0/100	-----	40,000	300	1.72

Example 3

Pellets having a density, compressive strength, thermal properties, detonation velocity, and explosive power comparable to those of the pellets described in Example 1(A) are obtained when the procedure of Example 1(A) is repeated with the exception that tetranitro-2,3,4,5-dibenzo-1,3a,6,6a-tetraazapentalene is substituted for the tetranitro-2,3,5,6-dibenzo-1,3a,4,6a-tetraazapentalene. Similarly, the procedure of Example 1(A) can be repeated except that an equal weight of TNT is substituted for the trinitrobenzene used in that example.

I claim:

1. An explosive composition comprising a mixture of at least one polynitro heterocyclic compound selected from the group consisting of tetranitro-2,3,5,6-dibenzo-1,3a,4,6a-tetraazapentalene and tetranitro-2,3,4,5-dibenzo-1,3a,6,6a-tetraazapentalene and about from 1 to 20%,

based on the weight of said mixture, of at least one aromatic compound of 6 to 7 carbon atoms bearing 3 nitro groups as the sole inorganic substituents.

2. A composition of claim 1 wherein said aromatic compound is 1,3,5-trinitrobenzene and is present in the amount of about 2 to 5%.
3. A composition of claim 2 wherein said polynitro heterocyclic compound is tetranitro-2,3,5,6-dibenzo-1,3a,4,6a-tetraazapentalene.
- 10 4. A composition of claim 2 wherein said polynitro heterocyclic compound is tetranitro-2,3,4,5-dibenzo-1,3a,6,6a-tetraazapentalene.
- 15 5. A shaped article having a density of at least about 1.70 grams per cubic centimeter comprising a compressed composition of claim 1.
